UNITED STATES PATENT OFFICE.

CAROLINE M. PRANGE, OF INDIANAPOLIS, INDIANA.

DARNING ATTACHMENT FOR SEWING MACHINES.

Application filed June 10, 1925. Serial No. 36,119.

In order that darning may be accomplished by the use of an ordinary sewing machine it is necessary that the material be not firmly held upon the feed plate, in order 5 that the material may be shifted in any direction by the operator.

There are at the present time on the market a number of so-called darning attachments for sewing machines which 10 involve the removal of the presser-foot and the substitution of another element in place thereof of such character that, while the needle will be properly guided, the work will nevertheless be left free from the influence of the feed plate of the machine. 15 Such devices are open to the objection that considerable time is required to remove the regular presser-foot and to substitute the darning device and also to the objection that 20 ordinary sewing operations may not be resumed until the regular presser-foot has been restored.

The object of my present invention is to provide a simple attachment, readily associated with most of the standard makes of 25 sewing machines and of such character that the ordinary presser-foot may be so influenced, without removal or change of attachment, as to free the work from the influence of the feed plate, the device being of 30 such character that it may be readily placed and removed and the function of the regular presser-foot readily restored.

The accompanying drawings illustrate my 35 invention.

Fig. 1 is a perspective view of my improvement, the adjacent portions of a sewing machine being indicated in dotted lines;

Fig. 2 is a side elevation of my improvement;

Fig. 3 is an elevation, at right angles to the plane of Fig. 2, of the upper portion of the device shown in Fig. 2, and

Fig. 4 is a section, on an exaggerated scale, 45 on line 4-4 of Fig. 2.

In the drawings 10 indicates a metal plate one end 11 of which is turned at right angles to the plane of the main body 10 and provided with an intermediate open ended slot 50 12, thus forming an end hook 13. The plate 10 is slotted at 14 and is slidingly mounted between the flanges 15 of a plate 16 which, at its lower end, is provided with a

pair of oppositely directed open slots 17, 17 thus providing fingers 18, 18 adjacent the 55 end of plate 16. Plate 16 carries a threaded stud 19 which is projected through slot 14 and provided with a clamping nut 20 the arrangement being such that the distance between fingers 18 and finger 11 may be 60 readily adjusted.

The slot 12 is formed to receive a projection 25 commonly found upon the heads 26 of most sewing machines and slots 17 are capable of receiving the usual lever 27 by 65 means of which the usual presser-foot 28 of a sewing machine is raised and lowered.

In use plates 16 and 10 will be relatively adjusted so that when either one of fingers 18 is slipped under the operating lever 27 70 the presser-foot 28 will be held up away from the work table just enough to free the work, whatever its thickness, from the influence of the feeder plate 29.

Only one finger 18 is necessary but I provide two such fingers, one at a slightly greater distance from the end of the plate than the other so that, without changing the adjustment at stud 19, the device may be used for handling either thick or thin material beneath the presser-foot 28. 75

I claim as my invention:

1. As an article of manufacture, a darning attachment for sewing machines comprising a pair of slidably associated plates 85 one having at its top a hooked end for detachable association with the sewing machine head and the other at its end having transversely extending fingers at different distances from its end for detachable 90 association with the presser foot control.

2. As an article of manufacture, a darning attachment for sewing machines comprising a pair of slidably associated plates one having a longitudinally extending slot, a bolt 95 secured to the other plate and said slot, and a nut for said bolt for clamping the plates together, one of said plates having at its top a hooked end for detachable association with the sewing machine head and the other plate 100 at its end having transversely extending fingers at different distances from its end for detachable association with the presser foot control.

3. As an article of manufacture, a darning 105 attachment for sewing machines comprising

a pair of slidably associated plates one having one end turned at right angles to the main body thereof and provided with an open ended slot to form a hook for detachable association with the sewing machine head, and the other having a transversely extending slot to form a transversely ex-

tending finger for detachable association with the presser foot control.

In witness whereof I, CAROLINE M. PRANGE 10 have hereunto set my hand at Indianapolis, Indiana, this 8th day of June, A. D. one thousand nine hundred and twenty-five.

CAROLINE M. PRANGE.
